(57) **CLAIM**

The ornamental design for a radiator grill for automobile, as shown and described.

DESCRIPTION

FIG. 1 is a perspective view of a radiator grill for automobile showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of a part of grill thereof.

The broken lines shown illustrate portions of the radiator grill for automobile that form no part of claimed design.
